ABSTRACT

An action game of skill having an extruded elongated cup support member on which a plurality of cylindrical bodies defining cups are mounted in spaced relation longitudinally of this elongated support member. The ends of the elongated support member are adapted to be held in the hands of the user and a ball is bounced or tossed from one cup to another cup by appropriate manipulation of the elongated support member.

BALL TOSSING GAME HAVING SLIDABLY ADJUSTABLE RECEPTACLES

BACKGROUND OF THE INVENTION

Field of the Invention

This invention relates generally to games and relates more particularly to action games of skill wherein a plurality of cups are mounted on a supporting member in spaced relation and a ball is bounced from cup to cup.

SUMMARY OF THE INVENTION

The invention is an action game device which comprises an elongated support member, the ends of which are adapted to be held in the hands of the operator. This support member may be of a suitable plastic and may be extruded. Along the top of the support member are a pair of oppositely arranged inturned flanges, the adjacent free edges of which are parallel and spaced laterally apart.

A plurality of cylindrical bodies or members of resilient material have diametrically positioned slots adjacent one end for reception of parts of respective flanges, the cylindrical members being adapted to be squeezed to reduce the distance of the slotted portions, so the slotted ends may be inserted between the flanges, with the slots aligned with the flanges. Then upon release of the squeezing pressure, the flanges will enter the slots for retaining the cylindrical members in place on the support member. The support member provides a bottom for the cylindrical members, thereby providing a series of cups.

These cups may all be of the same height, or they may be of different heights and may be variously arranged as to height. There is a ball of such size as to be easily received in the cups and this ball is bounced or tossed from cup to cup. Skill is required or developed to toss the ball from one cup and to catch it in another cup, usually, but not necessarily, an adjacent cup. This procedure or play may be continued for example until the player misses catching the tossed ball in a cup. Play may, for example be from successive cups from one end of the device to the other.

The characteristics and advantages of the invention are further sufficiently referred to in connection with the following detailed description of the accompanying drawings which represent certain embodiments. After considering these examples, skilled persons will understand that many variations may be made without departing from the principles disclosed and I contemplate the employment of any structures, arrangements or modes of operation that are properly within the scope of the appended claims.

BRIEF DESCRIPTION OF THE DRAWINGS

Referring to the drawings, which are for illustrative purposes only.

FIG. 1 is a perspective view of apparatus embodying the invention;

FIG. 2 is an enlarged sectional view taken on line 2-2 of FIG. 1;

FIG. 3 is a sectional view taken on line 3-3 of FIG. 2;

FIG. 4 is a perspective view of one of the cylindrical members defining a cup.

DESCRIPTION OF THE PREFERRED EMBODIMENT

Referring more particularly to the drawings there is shown apparatus embodying the invention, an elongated support member being indicated generally at 10.

Support member 10 has a general T shape in cross section, the stem of the T is in the shape of a U and is indicated generally at 12. The closed lower end 14 of 10 the stem connects the lower ends of the arms 16, there being outwardly extending parts 18 along the upper ends of said arms 16 and at the outer edges of said parts 18 there are respective upstanding parts 20 from the upper ends of which there are oppositely arranged in-turned flanges 22 spaced upwardly of the outwardly extending parts 18, said flanges being in a common plane with the inner free edges spaced apart in parallel relationship. The support member 10 may be of any suitable material such as a stiff plastic, for example, there being various well known plastic on the market suitable for this purpose for example.

There are a plurality of cylindrical members 26 each comprising a cylindrical wall 28 and defining what are termed cups herein, parts of the support member serving as the bottom for said cups as shown in FIGS. 2 and 3.

The cylindrical walls 28 of each member 26 have diametrically positioned slots 30 for reception of free edge portions of the flanges 22 of the support member to thereby hold the cylindrical members 26 in position on the support member.

Cylindrical members are of flexible, resilient material such as plastic for example, there being various suitable plastics presently on the market, such as for example Polystyrene, Polypropoline, Polyethelyne, etc.

The cylindrical members are placed on the support member by squeezing same at the slotted sides sufficiently to insert the lower ends between the free edges of the flanges 22, then allowing the cylindrical members to return to their normal cylindrical condition allowing free edge portions of the flanges to enter the respective slots.

The cups are open at their upper ends and said cups may be of different heights or they may be all of the same height. Where the cups are of different heights, they may be variously arranged, either progressively higher or lower or miscellaneous arranged.

A ball 34 sufficiently smaller in diameter than the inside diameter of the cups so as to easily be received therein. Any suitable ball may be used such as, for example, a Ping Pong ball or a styrene plastic practice golf ball, or a ball of any other suitable material may be used.

To use the apparatus the ends of the support member are held in the player's hands and with the ball 34 in one of the cups, such as an end cup for example the ball is tossed out of the cup and caught in the next cup. This procedure is followed from one end of the apparatus to the other.

The cups can be moved longitudinally by putting a little squeezing pressure thereon and sliding them to a desired position. Alternatively the cups can be squeezed enough to remove them and then they may be replaced at desired positions.

The invention and its attendant advantages will be understood from the foregoing description and it will be apparent that various changes may be made in the

form, construction and arrangement of the parts of the invention without departing from the spirit and scope thereof or sacrificing its material advantages, the arrangements hereinbefore described being merely by way of example, and I do not wish to be restricted to the specific forms shown or uses mentioned except as defined in the accompanying claims.

I claim:

1. In game apparatus, comprising :
an elongated cup support member;
a plurality of cups on said support member, said cups
being spaced longitudinal on the support member,
the support member having a pair of longitudinally

extending inwardly turned flanges, the free longitudinal parallel edges facing each other and spaced apart, and said cups including a cylindrical wall having slots adjacent one end for slidable reception of edge portions of said flanges.

2. The invention defined by claim 1, wherein the cylindrical wall of the cups is of resilient material.

3. The invention defined by claim 1, wherein the support member is of extruded plastic.

4. The invention defined by claim 3, wherein the cylindrical wall of the cups is of plastic and is extruded.
